UNITED STATES PATENT OFFICE

2,573,618

ELECTRIC DISCHARGE DEVICE

David Lorimer Smart, Stafford, England, assignor
to The English Electric Company Limited, Lon-
don, England, a British company

Application October 20, 1949, Serial No. 122,461
In Great Britain October 25, 1948

8 Claims. (Cl. 313—170)

1

This invention relates to electric discharge devices of the kind employing a liquid pool cathode and in which the main discharge is initiated by a subsidiary discharge taking place between the cathode and a movable ignition electrode.

In the past such an ignition electrode has been formed by or mounted on a movable or pivoted member arranged in a special side arm of the device, a coil being provided for magnetically influencing the member.

In order that the power required for moving the ignition and excitation electrode may be kept low, it is desirable that it should be almost balanced about a pivot, and it is convenient to lead the ignition current through the pivot of the ignition electrode. A difficulty, however, is that in the course of time one or other of the relatively movable portions of the pivot may become pitted, due to arcing, and the pivot is then apt to stick in one position.

According to a feature of the invention the pivot is formed of relatively movable elements having sufficient play to permit one element to roll upon the other in the operation of the ignition electrode.

In a preferred form of the invention the pivoted member is formed of a strip of metal doubled upon itself to provide a pair of parallel arms, each of the arms being provided with a pivot hole and a metallic pin supported from the envelope of the device passes through these holes with sufficient clearance to permit a rolling contact between the edges of the holes and the pin.

In an alternative form of the invention the pivoted member is provided with a pin extending therefrom and engaging in pivot holes in a pair of spaced supports.

According to a further feature of the invention the two elements of the pivot are of material or are covered with a thin layer of material which wets with the liquid cathode material so that a conducting layer of the latter is formed at least at the points of contact of the two elements. The elements of the pivot may also be arranged so that one of them forms a receptacle for a portion of the cathode material, on which portion the other element floats.

Several forms of the invention will now be described with reference to the accompanying drawings.

In these drawings Fig. 1 illustrates a portion of a discharge device incorporating a particular form of the invention. The discharge device is of the type known as an "Excitron" and has a glass envelope 1 containing an anode and grid,

2

and a cathode consisting of a pool of mercury 2. An ignition electrode consisting of a graphite rod 3 is arranged within the envelope on a pivoted arm 4 so that it may be moved into or out of contact with the cathode 2. The arm 4 consists of a strip of metal bent double to hold the electrode 3 at one end and to provide at the other end two spaced parallel members, one of which is shown at 4a, each formed with a hole 5. A supporting and current conducting wire 6 has a bent-over portion 6a which passes through the holes 5 and serves as a pivot pin. The portion 6a has a diameter about two-thirds of that of the holes 5. A lead-in wire 7 which is provided with vitreous insulation 8 and is sealed to an eyelet 9 welded to a metal portion of the envelope supports the wire 6 by means of a metal clip 10. Additional rigidity is provided by a further clip 11 secured to an electrode 12 of the device and engaging a glass bead 13 which surrounds an extension 6b of the wire 6.

A strip of iron 14 is welded to the end of the arm 4 to form an armature and is folded round a weight 15 which partially balances the electrode 3 and the other end of the arm 4 so as to reduce to a minimum the energy necessary for operation. A D. C. choke 16 is arranged outside the envelope 1 in such a way that its magnetic field extends to the position occupied by the upper end of the armature 14. In order to increase the strength of the field which influences the armature 14, the gap 17 of the choke is arranged adjacent this position.

Ignition current is supplied to the electrode 3 through the lead-in wire 7 and the choke 16 is included in series to provide smoothing. The electrode 3 is normally held by its own weight in contact with the mercury cathode 2 but when the ignition circuit is energised, current begins to flow and the magnetic circuit of the choke 16 becomes effective to attract the armature 14 towards the wall of the envelope 1, bringing the parts into the position shown in the drawing, and resulting in the formation of an arc between the electrode 3 and the cathode 2. A D. C. potential is used to supply the ignition circuit and the arc is maintained after ignition to serve as an excitation arc.

It will be seen that the ignition and excitation current is supplied through the pivot of the arm 4 and in normal operation pitting of the metal surfaces at this point is to be expected. Since, however, the holes 5 are considerably larger than the pin 6a, any pitting which may take place will have negligible effect on the satisfactory

movement of the arm 4. Furthermore, the arm 4 and the pin 6a are both plated with a material which wets with mercury so that the contact between the two parts is improved and arcing reduced and there will thus be less likelihood of pitting occurring.

Fig. 2 of the drawings illustrates diagrammatically a further form of ignition device. In this case the electrode 3 is arranged on the same side of the pivot 5 as the armature 14, being supported from the latter on an arm 4b. The armature 14 is carried as before on a pivoted arm 4 and in this case a balance weight 15 is arranged at the end of the arm 4 which is remote from the armature 14 and beyond the pivot 5. The balance weight 15 is chosen so as to permit the electrode 3 normally to dip into the cathode 2. The electrode 3 is withdrawn from the cathode 2 when a coil (not shown) arranged on the outside of the envelope 1 is energized.

What I claim as my invention and desire to secure by Letters Patent is:

1. An electric discharge device including at least an anode, a pool cathode and an excitation electrode normally in contact with the material of said cathode but arranged for movement away from said material under the influence of a magnetic field extending through a wall of the device, said electrode being mounted on a pivot formed of relatively movable elements having sufficient play to permit one element to roll upon the other in the operation of the excitation electrode.

2. An electric discharge device as claimed in claim 1, wherein said pivot is included in the conducting path for current supplied to said control electrode.

3. An electric discharge device including at least an anode, a pool cathode and an excitation electrode normally in contact with the material of said cathode but arranged for movement away from said cathode under the influence of a magnetic field extending through a wall of the device, said electrode being supported by a pivot formed of two relatively movable elements having sufficient play to permit one of said elements to roll upon the other in the operation of the excitation electrode, and at least the contacting surfaces of said elements being of a material which wets with the material of said cathode.

4. An electric discharge device as claimed in claim 3, wherein said pivot is included in the conducting path for current supplied to said control electrode.

5. An electric discharge device including at

least an anode, a pool cathode and an excitation electrode normally in contact with the material of said cathode but arranged for movement away from said material under the influence of a magnetic field extending through a wall of said device, said electrode being carried by a pivoted structure in the form of two spaced substantially parallel metal strips, provided with apertures through which extends a fixed supporting rod serving as part of the pivot and as a current conductor for said excitation electrode, said apertures being of sensibly greater diameter than said supporting rod.

6. An excitation electrode for a pool cathode electric discharge device including a member pivoted for movement into and out of the cathode material, said member being mounted on a current-carrying pivot formed of relatively movable elements having sufficient play to permit one element to roll upon the other in operation of said electrode.

7. The invention as defined in claim 6 wherein at least the contacting surfaces of said elements are of a material which wets with the material of said cathode.

8. The invention as defined in claim 6 wherein said electrode is carried by a pivoted structure in the form of two spaced substantially parallel metal strips, provided with apertures through which extends a fixed supporting rod serving as part of the pivot and as a current conductor for said excitation electrode, and said aperture being of sensibly greater diameter than said supporting rod.
